Giuseppe Preti, Ferrara, Italy, assignor to Jacob B.
Berland, Los Angeles, Calif.

Application March 3, 1953, Serial No. 23,893

Term of patent 7 years

(Cl. D7—7)

To all whom it may concern:

Be it known that I, Giuseppe Preti, a citizen of Italy, residing at Ferrara, Italy, have invented a new, original, and ornamental Design for a Shoe or Similar Article, of which the following is a specification, reference being had to the accompanying drawing forming a part hereof.

I claim:

The ornamental design for a shoe or similar article, as shown.

GIUSEPPE PRETI.
